DRUM STOP MECHANISM FOR ROTARY DUPLICATING MACHINES

Louis A. Smitzer, Chicago, Ill., assignor to Ditto, Incorporated, Chicago, Ill., a corporation of West Virginia

Application May 11, 1953, Serial No. 353,986

5 Claims. (Cl. 192—142)

This invention relates to an improved drum stop mechanism for rotary duplicating machines.

Duplicating machines may be designed to operate continuously for what may be termed as "straight duplicating," or they may be designed for "systems use" in which the drum rotates through a single cycle at a time and is automatically stopped at the end of each cycle.

In the single cycle type of operation, the drum may be stopped by mechanical blocking means, or by a non-positive or non-blocking type of stop means. The present invention relates to the latter type.

Co-pending Levin application Serial No. 108,741, filed August 4, 1949, now Patent No. 2,645,174 dated July 14, 1953, shows a non-blocking type of stop means which includes an electric clutch and brake mechanism. The arrangement shown in that application requires a rather complicated control circuit which alternately actuates the clutch and brake.

It is an object of the present invention to provide a duplicating machine having a much simpler control means therefor.

The present invention contemplates the use of a mechanical clutch and brake mechanism of the type shown in my co-pending application Serial No. 346,555, filed April 3, 1953, of which this application is a continuation-in-part.

According to the present invention, the non-blocking braking means is actuated by a weight or spring actuated device which eliminates the use of relays in the control circuit.

Another object of the present invention is to provide improved drive means for a rotary duplicating machine in which the cycle of operation may be initiated mechanically, as by a manual or foot operated control lever, and may be terminated by an electric control circuit which is actuated by the movement of the drum or other rotating part of the machine.

A still further object of the present invention is to provide an improved stop mechanism in which the drum may be selectively stopped in one of a plurality of positions.

Other objects, features and advantages will become apparent as the description proceeds.

With reference now to the drawings, in which like references designate like parts—

Fig. 1 is a diagrammatic representation of a preferred embodiment of my invention showing the relationship of the control unit to the other elements of a duplication machine;

Fig. 2 is an elevation of the control unit shown in Fig. 1; Fig. 3 is a plan view of the control unit of Fig. 2;

Fig. 4 is a sectional elevation taken along the line 4—4 of Fig. 3;

Fig. 5 is a detailed section taken along line 5—5 of Fig. 4, showing the manner in which the control rod engages the control ring;

Fig. 6 is a detailed view of the cam and cam actuated switches;

Fig. 7 is a wiring diagram;

2

Fig. 8 is a fragmentary vertical section taken along line 8—8 of Fig. 3; and

Fig. 9 is an enlarged sectional view taken along a generally cylindrical plane designated by the line 9—9 of Fig. 8, showing the cooperation between the control ring and its adjacent parts, the solid lines indicating the parts in braked position, and the broken lines indicating the parts in drive position.

The present invention is illustrated as applied to a duplicating machine of the wet process type, although it is equally applicable to certain other types of duplicating machines. As shown in Fig. 1, the duplicating machine may include a drum 10, a cooperating pressure roll 11, and a pair of feed rolls 12 and 13, which cooperate with each other and are disposed in front of the bite of the drum and pressure roll 10 and 11.

The feed rolls are driven intermittently from the drum so that during a portion of the drum revolution as the drum rotates continuously, the contacting feed rolls are stationary so that the bite of the feed rolls provides a stop against which the leading edge of a copy sheet may be positioned, thus to secure proper registration. Preferably, the feed rolls, or one of them, are driven through an overrunning clutch and are positively driven by the drum through only about 70° C. of the drum rotation, corresponding to the angle COD in Fig. 1. Thereafter, the feed rolls are dragged by the sheet, due to the provision of the overrunning clutch. An example of one such type of feed roll drive is shown in Levin application Serial No. 215,440, filed March 14, 1951, now Patent No. 2,740,353.

The drum 10 is provided with means for supporting a master sheet on its surface in a given position, such as the master clamp 14.

The drum 10 is driven from a motor 15 by means of a belt 16 which engages a pulley 17 fixed to or otherwise associated with the drum 10. The control unit includes a clutch 18, the output element of which is a driving pulley 19, which also engages the belt 16.

The drum, pressure roll and feed rolls are mounted in a suitable framework, not shown; the framework of the machine also includes a suitable support 20 for the motor 15 and clutch 18. A bracket 21 is provided for mounting the clutch; the bracket is mounted on a support 20, and the clutch is provided with a flange 22 which is suitably screwed to the bracket 21. The operation of the clutch is controlled by a control member which is in the form of a control ring 23, shown in Figs. 3 and 5.

The clutch 18 is shown and described in detail in the aforesaid co-pending application Serial No. 346,555, of which this application is a continuation-in-part. As described in said application, the clutch includes a brake ring 24a and a cooperating driven element 24b. The driven element is resiliently urged against a driver 70 by spring 24c. The brake ring 24a is nonrotatably mounted on flange 22, but is axially displaceable so that it may be urged into engagement with the driven element 24b to displace the same out of engagement with the driver and to cause the driven element to come to a stop. Axial displacement of brake ring is caused by counter-clockwise movement of the control ring 23 from the dotted line position to the solid line position, as shown in Fig. 5.

In other words, the brake ring 24a provides a non-blocking braking means which causes the drum to come to a stop.

As shown in Fig. 8, the driver 70 is pinned to a drive shaft 71 which is suitably journaled in a supporting sleeve 72, integrally formed with the flange 22. The driven element 24b, integral with pulley 19, is rotatably mounted on the drive shaft 71.

The control ring 23 is provided with a plurality of apertures 75. In each aperture, there is disposed a pair of

balls 76, such as ball bearing balls. As shown in Figs. 8 and 9, the control ring 23 is disposed between the flange 22 and the brake ring 24a. These members are provided with grooves to receive the portions of the balls 76 which project beyond the confines of the control ring, and at least one of these grooves constitutes a cam groove so that the brake ring can be displaced forwardly.

In the embodiment shown, the flange 22 is provided with a continuous groove 77 of uniform depth. The rear surface of the brake ring 24a is provided with a plurality of cam grooves 78, the depth of which tapers as shown in Fig. 9.

Both of the grooved elements, the flange 22, and the brake ring 24a, are stationary, in the sense of being non-rotatable. The control ring 23, on the other hand, is rotatably mounted on that portion of the supporting sleeve 72 which extends forwardly of the flange 22. Hence, as the control ring 23 is moved in the counterclockwise direction from the dotted line position in Figs. 5 and 9 to the solid line position which, in Fig. 9 is indicated by an upward movement, the right hand ball 76 will move upwardly in the cam groove and cause the brake ring to be displaced forwardly, or to the right, as shown in Fig. 9.

The present invention provides means for actuating the control ring so that the drum will be driven through a single cycle and then automatically stopped. This means includes a weight actuated means, a latch for maintaining the weight actuated means in an elevated position, and a drum actuated control circuit for releasing the latch.

The weight actuated means includes a control rod 25 which, as shown in Figs. 2 and 4, is slidably mounted in collars 26 formed on the bracket 21. Means such as weight 27 are provided to bias the control rod downwardly, the weight being mounted directly on the control rod. The control rod also carries a yoke member 28 which engages a lug 29 which forms a part of the control ring 23.

Since the movement of the control ring from its drive, or dotted line position, to its braked, or solid line position, involves work done against the force of the spring 24c, the mass of the weight 27 provides a source of kinetic energy to facilitate a rapid and certain operation of the clutch. Although other means such as a spring may be provided for biasing the control rod into its braked position, the gravity actuated weight 27 is preferred due to the kinetic energy provided.

Means are provided to restore the weight and control rod to their elevated position and to move the control ring 23 from its braked position to its drive position. This means, as shown in Fig. 1, comprises a lever 30 which is pivotally mounted on the support 20. The lever has a rounded end 31 which engages the head of a screw 32 which takes into the lower end of the control rod 25. As shown in Fig. 2, a lock nut 33 is provided so that the position of the screw may be securely adjusted; thus the screw and lock nut provide means for adjusting the throw of the control rod 25.

Rubber washers 34 may be provided to absorb any shock incident to the operation of the weighted control rod.

A foot treadle 35 may be pivotally secured to the base 36 of the machine. A link connects the foot treadle and the lever 30 so that the lever 30 may be conveniently operated by the operator's foot. A counter-balancing spring 38 may be provided so that the foot treadle 35 is biased into its up position.

In operation, when the foot treadle 35 is depressed, the control rod 25 and the weight 27 are elevated into the dotted line position, as shown in Figs. 1 and 5, thus initiating the cycle of operation. Means are provided to latch the control rod in this elevated position for the remainder of the cycle of operation.

As shown in Fig. 4, the control rod 25 is provided with a slabbed portion 40 on which rides a latch lever 41. The

lower end of the slabbed portion is provided with a notch 42 into which the latch lever drops when the parts are elevated. The latch lever is pivotally mounted in a forked lug 43 which forms a part of the bracket 21 by means of a pivot pin 44. A spring 45, shown in Figs. 3 and 4, urges the latch lever into engagement with the control rod 25. Another arm of the latch lever is engaged by the plunger 46 of a solenoid 47.

Thus, when the control rod is elevated by depression of the foot treadle 35, the spring 45 causes the latch lever to drop into the notch, thus maintaining the weight and control rod in their elevated or drive position. Operation of the solenoid will retract the latch lever, thereby causing the control rod to drop and actuate the non-blocking braking means embodied in the clutch 18.

A control circuit is provided to energize the solenoid 47. The control circuit includes notched cam means 50 which rotate with the drum and which actuate normally open switches 51 and 52. As diagrammatically shown in Fig. 1, the switches may be effectively spaced about 90° from each other to the end that a circuit through switch 51 will be closed 90° ahead of a circuit through switch 52.

As shown in Fig. 6, the notched cam means 50 may comprise a cam 50a having a notch 53, and a cam 50b having a notch 54. These cams 50a and 50b are coaxially mounted side by side on an extension of the drum shaft 56. By providing a separate cam for each switch, the two switches 51 and 52 may be mounted on a common mounting plate 55. The switches are vertically offset from each other so that cam 50a engages switch 51, and cam 50b engages switch 52. The cams may be adjustably mounted on the drum shaft 56 by means of set screws 57.

The position A of the drum shown in Fig. 1 may be considered the normal home position. In this position the master clamp 14 is readily accessible so that the master sheet can be readily changed when the drum is in its home position. Hence, when duplicating on sheets of normal length, the drum is caused to stop in its home position A.

However, when duplicating upon extra long sheets it is desired to cause the drum to stop in position B, so that the trailing edge of the master sheet and the superimposed copy sheet will clear the bite of the drum and pressure roll 10 and 11. The switch 51 causes the drum to stop in its home position A and the switch 52 causes the drum to stop in the extra long sheet position B.

Actually, the cams 50a and 50b are so adjusted that the arm 58 of switch 51 drops into the notch 53 about 30° to 45° prior to the time that the drum moves into its home position A. This is for the reason that the non-blocking braking means does not abruptly stop the drum; rather, a period of deceleration is required which is measured by the deceleration angle EOA. Similarly the cam 50b is adjusted to provide a similar deceleration angle with respect to position B.

The control circuit is shown in Fig. 7. The motor is connected across the power leads 60, 61, and an off and on switch 62 is provided for the machine as a whole. The cam switches 51 and 52 are connected in parallel with each other and each being in series with the solenoid 47. A three-way selector switch 63 is provided to establish a series circuit between one or the other of the cam switches and the solenoid 47, the circuit comprising these elements being connected across the power leads 60 and 61 and in parallel with the motor circuit. The selector switch is provided with three positions, 64, 65 and 66. In position 64, the operation of the solenoid is controlled by the cam switch 51; in position 66, it is controlled by cam switch 52. Position 65 is an open circuit position which corresponds to continuous operation.

Since each of the cam switches is actuated once during each rotation of the drum, the time, or point at which the control rod 25 is released can be determined by throwing the selector switch to one extreme or the other. When

in position 64, the drum will stop at its home position A. When in position 66, the solenoid will not be energized until the drum approaches the extra long sheet position B. When the selector switch is thrown into position 65, the solenoid will not be energized at all, with the result that the control rod will be maintained in its elevated drive position, and the drum will rotate continuously.

The operation has been described in detail in connection with the description of the various parts and sub-assemblies. To summarize, the drum and the feed rolls are driven by a continuously operating motor 15 through a mechanical clutch and brake device 18, the latter providing a non-blocking clutch action for starting the drum and a non-blocking brake action for stopping it. The mechanism of the clutch is described in detail in my aforementioned co-pending application.

The drum may be stopped either in position A or in position B, depending upon the throw of the selector switch 63. By providing a mechanical non-blocking brake or stop mechanism, I have found that a much smaller deceleration period or angle is required, as contrasted with an electric clutch and brake device.

Assuming that the single cycle operation on short sheets is desired, first the switch 62 is closed; then the selector switch 63 is thrown to position 64. The foot treadle 35 is depressed, which causes the drum to rotate and to come to rest in the A position. In this position, the master sheet can be affixed to the drum by the master clamp 14. Subsequent cycles of operation are effected merely by depressing the foot treadle 35 once for each cycle of operation.

For continuous operation, after the master sheet has been secured to the drum, the selector switch is thrown to position 65. The foot treadle 35 is depressed momentarily; the control rod is latched in its drive position for an indefinite period of time. At the conclusion of the continuous duplicating operation, the drum is stopped by throwing the selector switch into its position 64. This procedure would be followed for comparatively long runs, say 25 to 300 copies.

However, for short runs at continuous operation, it is more convenient for the operator simply to maintain the foot treadle 35 depressed.

For single cycle operation on extra long sheets, the drum is brought into its A position, as above described, for affixation of the master sheet. Then the selector switch is depressed and the drum will rotate up to position B. Thereafter, sheets may be individually fed into the bite of the feed rolls 12 and 13, and the foot treadle 35 depressed once for each operation, and the drum will come to rest, in each instance, in position B, in which the trailing edges of the master and copy sheets will be clear of the pressure roll 11.

The present invention requires no relays or low voltage relay circuits, hence the only power consumed by the control circuit is that small amount which is required to energize the solenoid once during each drum revolution. There is no power loss when the drum is stationary. The solenoid 47 may be a 120 volt alternating current solenoid so that it may be connected directly to the standard commercial source of electric power, as shown in Fig. 7.

The disclosure of my aforesaid copending application, Serial No. 346,555, is hereby incorporated, by reference, into this specification, insofar as consistent.

Although I have shown herein only a preferred embodiment of my invention, it will be understood that various changes may be made in the construction shown herein without departing from the spirit of my invention as pointed out in the appended claims.

I claim:

1. A duplicating machine comprising a drum, clamp means on said drum for engaging the leading edge of a master sheet supported on said drum, a pressure roll mounted for cooperation with said drum, a motor for driving said drum, clutch and brake mechanism inter-

posed between said motor and said drum and including a control member movable between drive and stop positions and a spring resisting movement of said control member into said stop position, means for actuating said control member in order to bring said drum to a stop in a home position in which the trailing edge of said master sheet will clear the bite of said drum and pressure roll, said means including a vertically disposed slidably mounted control rod engaging same, said control rod being weighted to bias the same toward stop position, manually operated means for elevating said control rod into a drive position wherein it displaces said control member into its drive position to initiate a cycle of operation of said drum, latch means for maintaining said control rod in drive position, means to release said latch means including a solenoid, and means controlled by the rotation of said drum for energizing said solenoid during each revolution of said drum so as to bring said drum to a stop in its home position, said weighted control rod providing a source of kinetic energy for displacing said control member against the bias of said spring, and said drum controlled means being operative prior to the time that said drum rotates into its home position so as to accommodate the time consumed by the gravity actuated movement of said control rod and the subsequent period of deceleration incident to the operation of said brake and clutch mechanism.

2. In a duplicating machine having a drum, stop means for said drum, and control means for actuating said stop means in one of a plurality of angular positions of said drum to cause said drum to come to a stop in one of a plurality of angular positions, said control means comprising cam means rotating with said drum, a plurality of normally open cam switches engaging said cam means, each cam switch being disposed at a different effective angle with respect to said cam means so that said cam switches will be sequentially operated, a control member for said stop means movable between drive and stop positions, means for actuating said control member including a slidably mounted control rod engaging same, means biasing said control rod into its stop position, means latching said control rod in its drive position, electrically actuated means for releasing said latching means, a circuit including said electrically actuated means and said plurality of cam switches, said cam switches being connected in parallel with each other and each being connected in series circuit with said electrically actuated means, and a multiple position selector switch in said electric circuit for providing connection between a source of power and one or the other of said cam switches whereby said electrically actuated means may be energized by the operation by one or the other of said cam switches to cause said drum to be stopped in one of a plurality of positions.

3. A duplicating machine as claimed in claim 2 including manually actuated means arranged to engage said control rod to shift the same into its drive position.

4. A duplicating machine as claimed in claim 2 in which said cam means comprises a plurality of axially aligned cams arranged side by side to each other, and in which said cam switches are offset one from the other in an axial direction so that each cam switch engages a different cam.

5. In a duplicating machine having a drum, stop means for said drum, and control means for actuating said stop means in one of a plurality of angular positions of said drum to cause said drum to come to a stop in one of a plurality of angular positions, said control means comprising a cam rotating with said drum, a plurality of normally open cam switches engaging said cam, each cam switch being disposed at a different effective angle with respect to said cam so that said cam switches will be sequentially operated, a vertically disposed slidably mounted weighted control rod for said stop means movable between drive and stop positions and biased into its stop position, means latching said control rod in its drive posi-

tion, electrically actuated means for releasing said latching means, a circuit including said electrically actuated means and said plurality of cam switches, said cam switches being connected in parallel with each other and each being connected in series circuit with said electrically actuated means, and a multiple position selector switch in said electric circuit for providing connection between a source of power and one or the other of said cam switches whereby said electrically actuated means may be energized by the operation of one or the other of said cam switches to cause said drum to be stopped in one of a plurality of positions.
